UNITED STATES PATENT OFFICE

2,646,179

LATCH TRIPPING DEVICE

Hugh W. Sanford, Jr., Knoxville, Tenn., assignor
to The Sanford Investment Company, Wil-
mington, Del., a corporation of Delaware

Application April 22, 1947, Serial No. 743,081

5 Claims. (Cl. 214—58)

1

This invention relates to improvements in latch tripping devices, and more particularly for controlling the release of the latches of drop bottom mine cars or other conveyances that include drop bottom doors.

This invention is an improvement particularly on the latch tripping mechanism, as set forth in the prior application of Hugh W. Sanford, Serial No. 526,426, filed March 14, 1944, which has issued as Patent No. 2,458,738. In said prior application, a protecting plate extended outwardly from the end bumper over a projecting shaft on which the latches were fixed and which shaft also carried a lug in position to be engaged by a tripping device mounted in the trackway, and which tripping device engaged the lug and passed through a notch in the protecting plate. Such device utilized a shaft that extended a considerable distance out from the side sill, so that the tripping device would clear the car wheels and hubs, that presented some objection in certain installations thereof.

An object of this invention is to improve the construction of the tripping device, to eliminate the necessity for a notch in the protecting end plate, to locate the tripping mechanism as close as practical to the end sills and thereby shorten the protecting plate and the rocker shaft on which the latches are mounted.

Another object of the invention is to provide an unlatching means for a drop bottom car where there is no latch lever or other device projecting out beyond the side of the car in an unprotected position, and where there is no unlatching means between opposite sides of the track, and so arranged that several unlatching devices can be used to dump the car selectively at different positions in the bin or hopper without interference with the open doors hanging down between the rails, of cars that have been unlatched or dumped previously.

A further object of the invention is to provide latch tripping mechanism for a drop bottom car or other conveyance which will be operated by a latch tripping device spaced laterally outside of the side sills and yet will be pushed down by the car wheel treads or hubs, as the car moves thereover, either forward or backward, and still will accomplish the desired tripping operation during the forward movement of the car over the device, while the engaging lug that is connected through a rocker shaft with the latches is located in a protected position.

These objects may be accomplished, according to one embodiment of the invention, by

2

mounting the latch or latches that control the car doors on a rocker shaft that projects outside of the side sills and side walls of the car or conveyance, with an operating lug thereon, which lug is mounted in a protected position behind a projecting plate or portion of the end structure of the car. This lug is in position to be engaged by a tripping arm mounted in the trackway, as the car moves forward thereover, which arm extends up into the space behind the protecting plate into position for engaging the lug.

Means is provided operatively connected with the tripping arm for controlling the raised or lowered positions thereof, and adapted to be engaged by the wheel tread or hub of the wheel of the car passing thereover or the engagement of a lever arm with the protecting plate passing thereover for depressing the tripping arm until the latter will clear the protecting plates of the car and thereafter rise up into the space behind the protecting plate in position for engaging the operating lug. Provision is made for depressing the tripping arm automatically after operation of the latches, to clear the end plate, as the car passes over and beyond the tripping device.

This form of the invention is illustrated, together with a modification thereof, in the accompanying drawings in which:

Fig. 1 is a side elevation of a car showing one form of latch tripping device associated therewith;

Fig. 2 is a cross section therethrough, with parts broken away and omitted for clearness of illustration;

Fig. 3 is a similar view at right angles thereto; Fig. 4 is a detail cross section on the line 4—4 of Fig. 2; and

Fig. 5 is a side elevation showing a modified form of tripping device.

The invention is shown as applied to a drop bottom mine car adapted for the conveying of coal or other loose lading from a receiving point to a pit or other point of discharge. The mine car is shown generally of the type set forth, for instance, in Patent No. 2,001,471, granted May 14, 1935, representing a four-wheel mine car having three drop bottom doors, adapted to travel on a track formed by a pair of rails designated generally R.

The general structure of the car comprises side and end wall structures 1 and 2, respectively, the side wall structures 1 rising from a pair of oppositely disposed side sills 3 connected together at the ends of the car by means of combined

end-sills and bumpers designated generally 4. Each end-sill 4 includes an end plate 7, fixed to the end wall 2. The side and end-sills 3 and 4, constitute the frame structure of the car for supporting the lading body of the car. The flaring side walls 1, rise upward at acute angles to the horizontal from the upper edges of the side sills 3.

The car is supported on wheels 5 and axles 6. The flaring sides 1 of the body are cut away to receive the wheels, which are deeply inserted therein beneath wheel hood coverings 8. Wheel hubs 9 cover the ends of the axles 6.

The car is shown as of the character provided with three drop bottom doors adapted for discharge in one-two-three order from front to rear of the car, which doors are designated respectively 10, 11 and 12. Any desired door structure may be used in which the doors are hinged for downward swinging movement. Such drop bottom mine cars usually employ doors hinged at their forward ends and are interconnected so that the middle and rear doors support the free edge of the next forward door, while the rear door is latched and may be released for dropping of all of the doors. Where these are adapted for discharge in one-two-three order, as shown in Patent No. 2,001,471, the doors are mounted for longitudinal sliding movement, as well as hinging movement about their hinge axes.

Thus upon release of the rear door it may drop sufficient to drag and move bodily rearward, thereby releasing the free edge of the middle door which will likewise move downward and rearward releasing the free edge of the forward door. This occurs usually just before the car reaches the bin and permits dropping of the forward door for discharge of the lading as soon as room enough is provided in the bin therebeneath, the other doors dropping in succession during forward movement of the car over the bin, in one-two-three order from front to the rear of the car.

As shown in Figs. 1 to 4, provision is made for latching the free edge of the rearward door 12 for thereby holding the doors 10, 11 and 12 in their closed positions, retaining the lading in the car until the latching means is released for dumping. For this purpose latches 18 are provided adjacent the rear end of the car, preferably spaced transversely on opposite sides of the center of the car, and pivotally supported by a rocker shaft 19, extending transversely thereof, on which said latches are fixed for swinging movement.

Each of the latches has a concave seat 20 (Fig. 4) formed therein in position to engage the trunnion 17 attached to the free edge of the rearward door 12 to support said rearward door in closed position, as shown in Fig. 4. The seat 20 is located on the opposite side of the vertical plane passing through the axis of the shaft 19 from the door 12, so that the weight of the door and the lading thereon tends to maintain the latched relation without any tendency for this weight to push the latch to one side. This is particularly true because of the concave shape of the seat 20 engaged by the convex end of the trunnion 17, whereby any movement of the latch tending to release the door must first raise up the free edge of the door.

The shaft 19 is journaled in brackets 21 fixed to the end structure of the car, and is so disposed relative to the adjacent end-sill 4 as to locate the latches 18 forwardly of the rear end-sill. The latches 18 are of a size such that their lower end portions do not project below the lower edge of the adjacent end-sill, and are disposed within

the space between the rear door 12 and the rear end-sill 4 in protected positions. This prevents disarrangement of the latches or accidental injury thereto in the event of wreckage of the car, as occurs frequently in mine operation, thus insuring adequate protection of the latches to maintain them in proper operating positions.

The latches 18 and their supporting shaft 19 are protected from the lading in the car by a guard or deflecting plate 22 that extends thereover and is fixed to the car end wall structure 2. The plate 22 is rigidly fixed by rivets or welding to the end wall structure.

Provision is made for supporting each latch 18 in its door-engaging position, for which purpose I have provided a coiled spring 23 interposed between a bracket shelf 24 and the latch 18 at the upper end thereof.

Each of the latches has a lateral pin 26 attached thereto and projecting through a slot 27 in the adjacent portion of the bracket 21. The pin 26 normally seats on the lower end of the slot 27 to limit the forward swinging movement of the latch 18.

The latch supporting shaft 19 projects laterally through the flaring side wall of the car, but terminates at a point spaced inwardly from the vertical plane of the adjacent flaring side wall at the point where it extends out farther laterally. The projecting end of the shaft 19 is supported in a hanger bracket 28 suspended from the flaring side wall 1. The extreme end of the shaft 19, externally of the bracket 28, is preferably square or of the other polygonal shape, as at 29, to receive a monkey wrench, socket wrench, or other means of turning the shaft manually to release the latches and thus dump the lading even when the car is in a stationary position.

While the shaft 19 is protected by the flaring side wall of the car, further protection is afforded against damage from obstructions in the mine or elsewhere, by locating the shaft in protected position between projecting portions of the opposite car ends or end-sill structures. Each car end structure has a laterally projecting plate 7 extending outwardly beyond the end of the shaft 19, as shown in Fig. 2, and normally below the latch actuating means mounted thereon. The plate 7 has a notch 30 in the path of the tripping mechanism mounted at the track to permit access of the tripping mechanism to the latch actuating means mounted on the shaft 19. While the plate 7 is shown as having the notch 30 in the lower edge thereof, this notch is not required necessarily and may be omitted, if desired.

In the form illustrated, the shaft 19 preferably extends only a short distance outside of the side wall 1 of the car, as shown in Fig. 2, with the projecting end thereof relatively close to the side sill 3, which lessens the danger of injury to the shaft in the event of wrecking the car.

A lug or operating member 32 is fixed rigidly on the projecting end of the shaft 19, preferably just inside of the hanger bracket 28, and also in protected position behind the protecting plate 7, as it projects outwardly from the end-sill structure. This projecting portion of the plate 7 at each end of the car extends laterally sufficiently to protect and confine behind the plate, the major portion of the length of the projecting end of the shaft 19, and also the operating member 32. If the notch 30 is used in the lower edge of the plate 7, the operating member 32 has its lower end terminating preferably above the upper edge of the notch, so said operating member is entirely pro-

5

tected by said plate against danger of accidental contact with objects along the trackway, which might engage the operating member to trip the car prematurely or cause injury or damage to the car latch mechanism.

The tripping device is mounted in the trackway in a position laterally of the rail R, on a suitable support mounted in the trackway. In the form illustrated in Figs. 2 and 3, this tripping device includes a tripping arm illustrated generally at 33, extending upwardly and forwardly relative to the direction of movement of the car along the trackway, carrying a tripping hook 34 on the upper end thereof. The tripping hook 34 is in position to engage a notch 31 in the latch operating member 32, as shown in Fig. 3, as the car moves over the tripping device. The contacting faces of the notch 31 and hook 34 are so arranged that the engagement will be maintained therebetween as the car moves along the trackway over the tripping device. This will cause swinging movement of the operating member 32, turning the shaft 19 to release the latches 18 from the door.

The tripping arm 33 is fixed on a shaft 35, journaled in a bearing box 36 in the trackway. Also fixed to the arm 33 or to the shaft 35 is a depending lug 37 connected at its lower end with one end of a coiled spring 38. The opposite end of the coiled spring 38 is connected with a screw member 39, held in adjusted relation by a bracket 40 fixed in the trackway. The spring 38 acts on the lug 37, normally tending to hold the tripping arm 33 in its elevated position until depressed by the passage of the car thereover. The tension of the spring may be adjusted by the adjustment of the screw member 39 relative to the bracket 40.

Also fixed on the shaft 35 at a point spaced inwardly from the tripping arm 33 is a lever arm 41 that extends substantially parallel with the tripping arm 33, as shown in Fig. 3. The upper end of the lever arm 41 is pivotally connected through a bolt 42 in a slot 43 formed in a link or lever member 44. The link 44 extends downward to a pivotal support 45, on which it is mounted in a bearing box 46 at a suitable point in the trackway.

The upper face of the lever arm 41 has fixed thereto a wedge-shaped contact member 47, which may be an integral part of the lever arm, and which contact member has an inclined edge portion in position to be engaged by the protecting plate 7, as the car passes thereover for depressing the tripping device sufficiently to clear the end-sill structure including the projecting portion of the plate 7. Then upon release of the pressure from the tripping device, the spring 38 will cause the tripping arm 33 to be raised into the path of the operating member 32, as shown in Fig. 3. When these parts 32 and 34 are engaged as shown, the continued movement of the car over the tripping device will cause a swinging movement of the operating member 32 to the dotted line position, shown in Fig. 3, thereby swinging the latch hooks 18 to release the door. As the guide member 47 reaches the relative position, shown in dotted lines in Fig. 3, the curved surface of this member will engage the lower edge of the plate 7, as it projects from the end structure, to cause a deflecting action of the tripping device, and a positive lowering of the tripping arm 33 and hook 34, underneath the end-sill structure and plate 7, out of position to be struck thereby.

The wheels 5 will roll over the tripping device, engaging both the lever arm 41 and the link 44,

6

which are connected together, so as to cause the tripping arm 33 and hook 34 to be lowered so long as a wheel or the hub 9 thereof, is in engagement with either of these elements 41 or 44. After passage out of contact therewith, the operating hook 34 will be raised into position to engage the operating member 32 by the action of the spring 38, and then to be deflected under the plate 7, permitting the car to pass over the tripping device.

A modified form of tripping device is shown in Fig. 5, in which the operating member on the shaft 19 is designated 50. This operating member is in position to be engaged by a tripping arm 51, that extends upwardly and rearwardly relative to the direction of travel of the vehicle, and has the upper end in position to engage the forward face of the operating member 50 to rotate the shaft 19 for release of the latch hooks.

The upper end portion of the tripping arm 51 carries a deflecting member 52, which has an inclined upper edge in position to engage under the end plate 7 to depress the tripping arm in properly timed relation for passage of the car over the tripping device, substantially in the manner described above in connection with Figs. 1 to 4. This tripping arm 51 and deflecting member 52 may be engaged and depressed either by the wheel treads or hubs of the wheels, as the car passes over the tripping device, which will cause a lowering movement of the tripping arm until it is raised into proper position for operating the member 50.

The tripping arm 51 is mounted on a shaft 35 and is fixed to a depending lug 54. The lower end portion of the lug 54 is connected with one end of a spring 55, the opposite end of which spring 55 is anchored at 56. The tension of the spring normally tends to raise the tripping arm 51 to its operating position.

This arm may be lowered manually when desired, as for the passage of cars over the tripping device without dumping, as shown in Fig. 5. A flexible device 57 is shown as connected with the lower end portion of the lug 54, and extending therefrom to the lower end of a lever 58. The lever 58 is pivotally mounted at 59. Thus upon swinging movement of the lever 58 in a clockwise direction, as shown in Fig. 5, the lower end of the lug 54 will be moved toward the left to cause a lowering action of the tripping arm 51, permitting passage of the cars thereover without dumping.

This invention makes it possible to protect the latch means on the car against danger of striking obstructions along the trackway, eliminating the latch lever or other device projecting out beyond the side of the car in an unprotected position as has been used heretofore. Moreover, the unlatching or tripping means can be used to dump the cars selectively at different positions in the bin or hopper without interference by the open doors hanging between the rails, of cars that have been unlatched or dumped previously.

While the invention has been illustrated and described in certain embodiments thereof, it is recognized that variations and changes may be made therein, without departing from the invention, except as specified in the claims.

I claim:

1. In conveying mechanism including a dumping conveyance mounted on a trackway and having a frame structure with transverse end portions and projecting portions therebetween, a

drop bottom door mounted on the frame structure for opening movement relative thereto, latch means for holding the door closed and movable to release said door for dropping, a shaft connected with the latch means for moving the latch means to release the door, said shaft extending transversely of the conveyance and having an end portion thereof projecting externally of the frame structure, an operating member mounted on the projecting end portion of the shaft, said frame structure including a portion extending laterally of the conveyance in overlapping relation with the operating member and the projecting portion of the shaft and with said operating member and shaft disposed approximately above the lower edge of said projecting frame portion in protected positions, tripping mechanism mounted in the trackway in position laterally of the frame structure when the conveyance is in dumping position, means mounting said tripping mechanism for raising and lowering movements of the tripping mechanism relative to the operating member, said tripping mechanism being in position for engagement by the projecting portion therebetween of the conveyance to be depressed beneath said portion and for raising movement into engagement with the operating member at a point above the lower edge of said laterally extending portion of the frame structure, said tripping mechanism including a tripping member in position for engaging the operating member, a link, and a lever member connected with the tripping member and pivotally connected with the link and arranged in position for engagement by the laterally extending portion of the conveyance for lowering the tripping member during passage thereover of said laterally extending portion of the conveyance.

2. In conveying mechanism including a dumping conveyance mounted on a trackway and having a frame structure with transverse end portions and projecting portions therebetween, a drop bottom door mounted on the frame structure for opening movement relative thereto, latch means for holding the door closed and movable to release said door for dropping, a shaft connected with the latch means for moving the latch means to release the door, said shaft extending transversely of the conveyance and having an end portion thereof projecting externally of the frame structure, an operating member mounted on the projecting end portion of the shaft, said frame structure including a portion extending laterally of the conveyance in overlapping relation with the operating member and the projecting portion of the shaft and with said operating member and shaft disposed approximately above the lower edge of said projecting frame portion in protected positions, tripping mechanism mounted in the trackway in position laterally of the frame structure when the conveyance is in dumping position, means mounting said tripping mechanism for raising and lowering movements of the tripping mechanism relative to the operating member, said tripping mechanism being in position for engagement by the projecting portion therebetween of the conveyance to be depressed beneath said portion and for raising movement into engagement with the operating member at a point above the lower edge of said laterally extending portion of the frame structure, said tripping mechanism including a tripping member in position for engaging the operating member, a link, a lever member connected with the tripping member and pivotally connected with the link and arranged in position for engagement by the laterally extending portion of the conveyance for lowering the tripping member during passage thereover of said laterally extending portion of the conveyance.

the link and arranged in position for engagement by the laterally extending portion of the conveyance for lowering the tripping member during passage thereover of said laterally extending portion of the conveyance, and means for automatically raising the tripping member into position for tripping engagement with the operating member upon release of the lever member and link from engagement therewith of the projecting portions between the end portions of the conveyance.

3. In conveying mechanism including a dumping conveyance mounted on a trackway and having a frame structure with transverse end portions and projecting portions therebetween, a drop bottom door mounted on the frame structure for opening movement relative thereto, latch means for holding the door closed and movable to release said door for dropping, a shaft connected with the latch means for moving the latch means to release the door, said shaft extending transversely of the conveyance and having an end portion thereof projecting externally of the frame structure, an operating member mounted on the projecting end portion of the shaft, said frame structure including a portion extending laterally of the conveyance in overlapping relation with the operating member and the projecting portion of the shaft and with said operating member and shaft disposed approximately above the lower edge of said projecting frame portion in protected positions, tripping mechanism mounted in the trackway in position laterally of the frame structure when the conveyance is in dumping position, means mounting said tripping mechanism for raising and lowering movements of the tripping mechanism relative to the operating member, said tripping mechanism being in position for engagement by the projecting portion therebetween of the conveyance to be depressed beneath said portion and for raising movement into engagement with the operating member at a point above the lower edge of said laterally extending portion of the frame structure, said tripping mechanism including a tripping member mounted in the trackway in position for raising and lowering movements relative thereto and adapted to engage the operating member to release the latch, and lever members connected with the tripping member and pivotally connected together, said lever members being mounted laterally of the tripping member and laterally outside of the frame structure in position for engagement by the laterally extending portion of the frame structure of the conveyance during movement of the conveyance over the tripping mechanism to depress the tripping member out of engagement with said operating member.

4. A latch tripping device adapted to control the release of a drop bottom door on a conveyance, comprising a tripping member having an engaging portion thereon adapted to engage latch release mechanism on the conveyance, a shaft mounting the tripping member for raising and lowering movements, spring means connected with the shaft and rotating the shaft and normally tending to urge the tripping member to a raised position, a lever member fixed to the shaft and turning therewith and extending upwardly therefrom substantially parallel with the tripping member, and a second member operatively connected with the upper portion of the lever member and extending laterally in the opposite direction therefrom, said lever member and sec-

ond member being adapted to be engaged by under portions of the conveyance.

5. A latch tripping device adapted to control the release of latch means of a drop bottom door on a conveyance, comprising a pair of lever members inclined toward each other, means pivotally connecting adjacent end portions of said members together for raising and lowering movement, means pivotally mounting the lower end portions of said members for relative swinging movement, resiliently acting means normally tending to urge said members to a raised position, and a latch release member connected with said members for operation thereby, said latch release member hav-

5
10
ing an upright abutment face thereon for engagement with the latch means.
